SURGICAL SUCTION AND IRRIGATION PUMP KIT

Paul E. Magers, R.D. 5, Melody Acres, Warsaw, Ind.

Filed Feb. 3, 1965, Ser. No. 83,673

Term of patent 14 years

(Cl. D83—12)

FIG. 1 is a side view of my new surgical suction and irrigation pump kit;

FIG. 2 is an end view of the surgical suction and irrigation pump kit of FIG. 1; and

FIG. 3 is a top view of the surgical suction and irrigation pump kit of FIGS. 1 and 2.

I claim:

The ornamental design for a surgical suction and irrigation pump kit, as shown.
